TANK CLOSURE MEANS

Oliver C. Ritz-Woller, Chicago, Ill.

Application March 26, 1932, Serial No. 601,310

7 Claims. (Cl. 220—86)

My invention relates to closure cap assemblies and particularly to a form of device suitable for use in connection with the usual filling opening of the gasoline tank on an automobile. It is the object of my invention to provide a new and improved form and arrangement of parts by which a closure cap member may be mounted and held in operative closure position by means which are readily releasable by a moderately strong direct pull thereon and in which improved means is provided in addition to the operative mounting means for attaching the cap so as to prevent separation of the cap from the tank farther than is necessary for convenient filling of the tank by the use of the usual hose. It is one of the objects of my invention to provide an improved attaching link of this type, preferably in the form of a yoke, and to provide improved means for permanently attaching the arms of the yoke to the cap member and to the tank so as to be effective for holding the cap when removed from the spout and so as to be readily slidably out of the way when the cap is returned to its closure position.

It is one of the objects of my invention to provide an arrangement of this type in a form comprising a foraminous member designed to be permanently secured in position on a tank so as normally to prevent the insertion of a siphoning tube effectively for an unwarranted withdrawal of the contents of the tank. It is one of my objects to provide an improved form of foraminous member preferably of sheet metal and having an elongated deeply dished conformation so as to prevent splashing of the gasoline when delivered to the spout under pressure for passage through the screen into the tank.

It is another of my objects to provide improved means for securing such foraminous member in position by which the member may be easily and quickly mounted in position upon the ordinary type of filling spout by any purchaser having little if any mechanical ability, and which serves effectively when once properly applied to resist any expedients likely to be employed for removing the member in connection with any probable efforts at petty thievery.

It is another object of my invention to improve devices of this type in sundry details hereinafter pointed out. The preferred means by which I have accomplished my several objects are illustrated in the drawings and are hereinafter specifically described. That which I be-

lieve to be new and desire to cover by Letters Patent is set forth in the claims.

In the drawings,—

Fig. 1 is a perspective view of my improved screen member and cap connected together in unit form with the cap in raised position with respect to the screen;

Fig. 2 is a central vertical section through my improved device in position upon a tank, with the cap lowered into its closure position, being substantially a section at line 2—2 of Fig. 4;

Fig. 3 is a side view of my improved device in position on a tank with the cap member raised out of closure position for permitting the insertion of a filling hose as shown in dotted lines;

Fig. 4 is a top plan view of the screen member of my device in position on the filling spout of a tank, the view being substantially a section taken at line 4—4 of Fig. 6;

Figs. 5 and 6 are vertical sections through my improved device in position on a tank, taken substantially at the lines 5—5 and 6—6 respectively of Fig. 4;

Fig. 7 is a perspective view of the filling spout of a tank with my improved device in position thereon, partly broken away, and showing a wrench about to be applied for rotating the device into operative gripping engagement with the spout; and

Fig. 8 is a perspective view of the top ring of my improved screen device showing the method of connecting the cap thereto.

Referring now to the several figures of the drawings in which corresponding parts are indicated by the same reference characters, 15 indicates a tank of any approved type having a filling spout 16 secured in position by means of an outwardly extending flange 17. At its upper end, the spout 16 is provided with an inwardly and downwardly extending flange 18 which is provided with notches 19 at opposite sides as is best shown in Fig. 4. As is best shown in Fig. 6, the lower edges of the opposite side portions of the flange 18 are obliquely disposed, the flange at each side slanting downwardly slightly from one of the notches 19 toward the other notch, and terminating adjacent to said other notch in a lug 20.

My improved screen device as best shown in Fig. 1 comprises a flat ring 21 to which are attached two separately formed sheet metal sections 22 of complementary form adapted together to provide an elongated cup shaped structure. As is clearly shown in Fig. 5, the flat ring 21 is provided at its inner edge with an annular flange 23 to which the upper ends of the screen members 22 are attached.

are connected, preferably by welding. As is best shown in Fig. 6, each of the screen sections 22 is provided at its lower end with outwardly turned lugs 24, the lugs 24 of the two sections being oppositely disposed as is best shown in Fig. 1 for enabling the two sections to be connected securely by a welding operation. Each of the sections 22 is formed of sheet metal having openings 25 therethrough at intervals along the screen both longitudinally and circumferentially thereof. As is also clearly shown in Fig. 1, the screen member is tapered toward its lower end.

At opposite sides, the foraminous sleeve comprising the screen member is provided with lugs 26 pressed outwardly from the sheet metal of the wall. The screen member is of such size as to be insertable readily into the spout 16 through the upper end thereof, the lugs 26 being adapted to pass through the notches 19 in the flange 18 so as to permit the plate 21 to be brought to rest upon the upper end of the spout 16, with gaskets 27 preferably interposed between the plate 21 and the end of the spout. As is clearly shown in Fig. 7, the plate 21 is provided at opposite sides with openings 28 therethrough into which the pins 29 of a wrench 30 are adapted to be inserted for applying power for giving the plate and the screen member a rotary movement with respect to the spout 16. The arrangement is such that when the plate 21 and the screen member are rotated in clockwise direction in Fig. 4 for bringing the lugs 26 carried by the screen member into engagement with the lugs 20 forming parts of the flange 18, such lugs 26 by their downward camming engagement with the flange serve to tighten the plate 21 firmly upon the spout 16. The arrangement is such that the openings 28 through the plate 21 are located directly above the notches 19 of the flange 18 when the lugs 26 reach the limit of their movement into engagement with the lugs 20 so that pins 31 driven downwardly through the openings 28 and through the gaskets 27 engage the ends of the notches 19, as is shown in Fig. 4 so as to prevent reverse rotary movement of the plate 21 and the screen member with respect to the spout 16. The pins 31 are of such size as to fit tightly in the openings 28 when driven down flush with the top face of the plate 21 as shown in Fig. 5. Inasmuch as the pins 31 extend downwardly inside of the spout 16 and between the wall of the spout 16 and the wall of the screen member, it will be appreciated that the pins are protected against ready removal from the plate 21, and the screen member itself is afforded corresponding protection against removal from the spout. The construction is such that any pur-chaser having little mechanical ability can easily apply the device in operative position by a rotary movement by the use of the wrench 30 and can then drive the pins 31 into position, making the device proof against any ordinary efforts at removal of the screen without the use of an extensive supply of tools.

For closing the upper end of the filling spout 16 and the upper end of the screen member 22, I have provided a cap comprising a plate 32 having an upwardly extending annular flange 33 about its edge. Such plate 32 is provided with a gasket 34 of cork or other suitable material on its bottom face held in position on the plate 32 by means of lugs 35 struck from the plate at intervals thereabout, as is best shown in Fig. 1. The gasket 34 forms the seat for the cap upon the ring 21 comprising the upper end portion of the screen member. On the upper face of the plate

32, I have provided a second plate 36 preferably of polished sheet aluminum such plate 36 having a downwardly extending annular flange 37 which is spun about the lower edge of the flange 33 for securing the plates 32 and 36 together. 5

The cap comprising the plates 32 and 36 is held yieldingly in position on the upper end of the spout 16 by means of a spring clip comprising a base portion 38 and two arms 39 formed integrally with said base from a strip of spring metal, 10 the arms 39 being provided with turned back arm portions 40 also formed integrally but pressed into channel form for giving them the desired rigidity. The arrangement is such that the lower ends of the arms 40 stand normally in such spaced relation to each other as to be adapted to enter the opening through the ring 21 and the flange 23, the arms 39 being adapted to yield inwardly toward each other from the position as shown in Fig. 3 to some such position as that shown in Fig. 2 for permitting engagement of the clip with the screen member below the flange 23, as is clearly shown in Fig. 2. The clip is mounted in position on the lower face of the plate 32 by means of metal discs 41 and 42 secured in position at opposite faces of the plate 32 cooperating with a plate 43 provided with lugs 44 at its corners, such lugs 44 extending through suitable openings in the discs 41 and 42 and being bent downwardly upon the face of the plate 41 for holding the parts clamped fixedly together. The base portion 38 of the clip extends between the disc 42 and the plate 43 so as to be held in position to resist any rocking movement of the clip with respect to the plate 32, the clip together with the discs 41 and 42 and the plate 43 being adapted to rotate freely with respect to the plate 32 upon an axis at right angles to said plate 32. 25

In the arrangement shown, a second spring clip comprising a base portion 45 is also secured in position between the plate 43 and the disc 42, such base portion 45 being disposed at right angles with respect to the base portion 38 of the first described clip. At its opposite ends the base portion 45 is provided with downwardly extending arms 46 formed integrally therewith, such arms 46 being in the arrangement shown of considerably greater length than the arms 39. The lower ends of the arms 46 extend through slots 47 provided at opposite sides of the ring 21, having their lower ends turned at an angle to provide outwardly extending lugs 48, such lugs 48 being preferably given an arcuate form for strengthening them substantially with respect to the arms 46 and for preventing such lugs from cutting into the gaskets 27 with which the lugs contact when the cap is supported in its raised position as hereinafter described. In Fig. 3, I have shown the metal of the ring 21 at one side of the slot 47 pushed upwardly with respect to the adjacent portions of the plate for permitting the lug 48 at that side to be inserted through the slot 47 after the arm 46 at the opposite side has been threaded through its slot 47. After the arms 46 have been inserted through the slots 47 under conditions as shown in Fig. 3, the metal is hammered or pressed down into normal position as shown in Fig. 6, whereupon the yoke comprising the base 45 and the arms 46 is held permanently in position. 50

The slots 47 are of such size as to permit the arms 46 to slide readily therethrough. The arms 46 accordingly present no appreciable resistance to the movement of the cap into its normal closure position as shown in Fig. 2, with the gas- 75

ket 34 resting upon the ring 21, in which position the cap is releasably held by the spring clip comprising the arms 40 as above described. Whenever it is desired to remove the cap from the 5 spout, this can be readily accomplished by an upward pull directly thereon, the arms 46 sliding through the slots 47 freely until the lugs 48 stop the movement by engagement with the lower gasket 27. Each of the arms 46 is provided at its lower end portion with a notch 49 at each edge thereof adapted by engagement with the plate 21 at the end of the slot 47 to hold the 10 arm 46 in raised position when the arms and the cap are tipped to one side in such raised position as that shown in Fig. 3.

While I prefer to employ substantially the form of construction as shown in my drawings and as above described, it is to be understood that my invention is not limited to such form except 15 so far as the claims may be so limited by the prior art.

I claim:

1. A closure cap structure for the filling spout of a tank, comprising in combination an inwardly 20 and downwardly turned flange on the upper end of the spout, a foraminous member having laterally extending lugs adapted to pass downwardly through notches in said flange and adapted by a rotary movement to engage the bottom 25 edge of the flange for holding the member firmly in position on the spout, and a pin driven into position in said foraminous member after it is secured in position on the spout adapted by engagement with one of said notches to prevent 30 reverse rotary movement of the member, said pin in its operative position being protected by the spout from ready removal.

2. A closure cap structure for the filling spout of a tank, comprising in combination an inwardly 35 and downwardly turned flange on the upper end of the spout, a foraminous member in the form of a cup adapted when in position in the end of the spout to permit an ordinary filler hose to be inserted in the spout to permit the passage of gasoline through the member into the tank but to prevent the insertion of a siphoning tube into the tank, laterally extending lugs on said foraminous member insertable through notches at 40 opposite sides of said flange and adapted by a rotary movement to engage said flange for holding the member in position in the spout, and a pin driven into position in said foraminous member after it is secured in position by said lugs adapted by engagement with one of said notches in the 45 flange to prevent reverse rotary movement of the foraminous member, said pin in its operative position being protected by the spout against ready removal.

3. In a device of the type described, the combination of a flat ring of sheet metal having an annular flange at its inner edge, and a screen in the form of an elongated sleeve tapering downwardly toward its lower end and formed of a plurality of complementary sections of perforated sheet metal rigidly secured to said ring at their upper ends and rigidly secured to each other by means of oppositely disposed lugs at their lower ends.

4. In a closure means for the filling spout of a 70 tank, the combination of a screen member in the

form of a downwardly tapered sleeve of perforated sheet metal secured in said spout, a cap member, and two arms secured in spaced relation to each other on the inner face of said cap and held against angular movement with respect to the cap, said arms being slidably mounted in slots at opposite sides of the spout so as to extend between the wall of the spout and the wall of the sleeve and being at their lower end portions of such width with respect to the slots as to be capable when slid upwardly of being tipped edgewise into holding engagement with the slots for supporting the cap in raised position.

5. In a closure means for the filling spout of a tank, the combination of a screen member in the form of a downwardly tapered sleeve of perforated sheet metal secured in said spout, a cap member, two arms secured in spaced relation to each other and secured on the inner face of said cap so as to permit rotation of the cap with respect thereto about an axis parallel with said arms, a transversely disposed plate portion at the upper end of said spout having slots therethrough at opposite sides within which said arms are slidably and pivotally mounted so as to extend between the wall of the spout and the wall of the sleeve, and outwardly turned lugs on the ends of said arms serving to prevent removal of the arms from the slots.

6. In a closure means for the filling spout of a tank, the combination of a screen member in the form of a downwardly tapered sleeve of perforated sheet metal secured in said spout, a cap member, two arms secured in spaced relation to each other on the inner face of said cap and held against angular movement with respect to the cap, a gasket on the upper end of said spout, a plate rigidly mounted on said gasket and having slots therethrough at opposite sides within which said arms are slidably and pivotally mounted so as to extend between the wall of the spout and the wall of the sleeve, and outwardly turned lugs on the ends of said arms adapted by engagement with said gasket to limit upward movement of the arms through the slots, said lugs being rounded upwardly at their intermediate portions for strengthening the lugs and for affording rolling engagement with said gasket.

7. In a closure means for the filling spout of a tank, the combination of a screen member in the form of a downwardly tapered sleeve of perforated sheet metal secured in said spout, a cap member, two arms secured in spaced relation to each other and secured on the inner face of said cap so as to permit rotation of the cap with respect thereto about an axis parallel with said arms, a transversely disposed plate portion at the upper end of said spout having slots therethrough at opposite sides within which said arms are slidably and pivotally mounted so as to extend between the wall of the spout and the wall of the sleeve, and outwardly turned lugs on the ends of said arms serving to prevent removal of the arms from the slots, said arms being notched at their lower end portions for permitting the arms to tip to one side in said slots and arranged so that the arms by engagement of the notches with said slotted plate portion support the cap in raised position.

OLIVER C. RITZ-WOLLER.
